UNITED STATES PATENT OFFICE

2,345,675

MANUFACTURE OF MATTRESSES

Harold Kibitz, Oak Park, Ill., assignor to J. W. Droll Company, Chicago, Ill., a corporation of Delaware

Application December 15, 1941, Serial No. 422,998

2 Claims. (Cl. 5—351)

The invention relates to the manufacture of mattresses.

One object of the invention is to provide an improved method of making mattresses of the type in which quilted pads form the top and bottom of the mattress and by which a strip of material which is secured to the pad outwardly of its inner liner and inwardly of the outer liner is folded around the border-member of a spring-structure and the filling beneath the pad to firmly retain the outer liner of the pad in its normal shape.

Another object of the invention is to provide an improved construction of mattress in which a strip which is secured to the pad outwardly of its inner liner is folded and secured around the filling under the pad and a portion of the filling in the pad to effectively secure the pad and filling to the border-members of the spring-structure.

Other objects of the invention will appear from the detailed description.

The invention consists in the several novel features which are hereinafter set forth and are more particularly defined by claims at the conclusion hereof.

In the drawing: Fig. 1 is a sectional view of a spring-structure with the filling thereon before the pad is placed on the filling. Fig. 2 is a section illustrating the quilted pad having a strip inserted in the padding material therein around its border laid on the filling over the spring-structure, before the pad is secured to the spring-structure. Fig. 3 is a section illustrating the insert-strip of the pad lapped around the border-strip of the spring-structure and extended around and secured by staples before the pad is secured to the boxing. Fig. 4 is a section illustrating a portion of the completed mattress.

In making a mattress in accordance with the present invention an assembled spring-structure is used to form the center of the mattress. This structure usually comprises top and bottom border helicals 20, helicals 20^a extending between and connected to the ends or sides of the border-helicals and springs 21 between and having their upper and lower ends respectively connected to the top and bottom helicals of the spring-structure, as well understood in the art. A filling 22 is first laid, as illustrated in Fig. 1, over the top of the spring-structure, with its marginal portion 22^a projecting outwardly sufficiently from the border-members to provide a portion which can be turned and folded under the border-

members 20 of the spring-structure. This filling 22 usually consists of sisal and cotton both of the necessary thickness to adequately cover the openings in the spring-structure.

5 A quilted pad is used to form the outer faces of the mattress and this comprises an inner liner 23 of material such as muslin, an outer member of ticking 24, and an intermediate layer of cotton, all of which are stitched together, as at 26, 10 and constitute a preformed pad. The inner liner terminates inwardly of the margin of the padding 25. The ticking forms the outer face of the mattress. The outer margin of the ticking 24 is usually hemmed, as at 27, for subsequent 15 connection to the boxing forming the sides and ends of the mattress. Along the entire margin of the quilted pad the filling 25 is divided horizontally into inner and outer layers 25^a, 25^b by a strip 28 of cloth, such as muslin, which is 20 stitched to the pad by a seam 29 inwardly of the margin of the pad. The outer margin of the strip 28 normally projects outwardly from the margin of the padding 25 and the inner and outer liners of the pad. The strip 28 is used to secure 25 the pad over the filling 22 and to the border-members of the spring-structure, as hereinafter described.

The next step in making the mattress consists in securing the filling and pad to the border-members of the spring-structure. The marginal portion 22^a of the filling 22, the layer 25^a of the padding 25, and the strip 28 are folded around the border-member 20 of the spring-structure and staples 30 are driven through the 30 strip 28, layer 25^a of the pad 25, and filling 22 inwardly of the border-member 20. The staples pass through the portions of strip 28 above and below the border-member. During this stapling 35 the strip 28 is drawn tautly around the layer 25^a of the padding and the portion of the filling 22 around which it is folded to compress them so that they will tightly secure the filling and inner portion of the pad around the border-member of the spring-structure. During this stapling 40 operation, the outer margin of the ticking 24 and the portion 25^b of the padding is turned upwardly so the staples can be driven inwardly of the border-member 20. This operation can be quickly effected by a suitable stapling machine 45 50 which is adapted to compress the strip and material within it around the border-member of the spring-structure while the staples are being driven. The strip 28 extends completely around the side and end margins of the mattress and 55 the staples are spaced apart so they will secure

the entire border of the pad and filling to the spring-structure. This securely connects the filling and pad to the border-members so that the border will conform and remain conformed to the borders of the spring-structure. An important result from the use of a strip interlaid in the padding of the quilted pad is that the tension of the strip 28 is applied to the pad outwardly of the inner liner, so the outer portion of the pad will be better held in shape than when the margin of the inner liner is used for that purpose. When one face of the spring-structure has been assembled with the filling and pad in this manner, the spring-structure is inverted and the filling and pad are assembled in the same manner to the other face of the spring-structure.

When quilted pads and fillings have been secured to both faces of the mattress, a preformed box-border comprising an outer strip 32 of ticking, an inner liner 33, and a filling 34 of felt, which have been stitched together, is fitted around the sides and ends of the spring-structure. The edge of the outer strip 32 is usually hemmed, as at 35. Next, the hemmed edge 27 of the ticking 24 of the quilted pad 24 and the hemmed edge 35 of the ticking 32 of the box-border are sewed together in a tape-edge stitching machine with a tape 36 around the seam to complete the mattress. In securing the box-border between the top and bottom of the mattress, the springs 21 are compressed to a certain degree so they will properly support the top of the mattress.

The invention exemplifies a method of making mattresses in which a marginal strip is interlaid with the padding of the quilted pad and secures a portion of the padding in the pad over the filling under the pad, and is folded around the border-member of the spring-structure by staples, so that the strip will hold a portion of the padding of the pad under the strip and over the border-member by said strip. The invention also exemplifies a mattress in which a strip interlaid in the padding of the pad secures the padding around the border-member of the spring-structure and exerts a pull on the pad outwardly of its inner liner. This strip aids in keeping the ticking-member 24 and the padding thereon more nearly taut than when only the inner liner is used to secure the pad to the border-member.

The invention is not to be understood as re-

stricted to the details set forth, since these may be modified within the scope of the appended claims, without departing from the spirit and scope of the invention.

Having thus described the invention, what I claim as new and desire to secure by Letters Patent is:

1. A mattress comprising, a central spring-structure including a border member; a filling over the spring-structure having its margins folded around the border-member; a quilted pad over the filling comprising an inner liner, an outer ticking sheet and padding all stitched together separately from the filling; a strip having its inner margin interlaid in the padding of, and secured only to, the pad, the underlying portion of the padding extending over the filling above the border-member, the strip extending over said underlying portion of the padding and being folded around and under the filling around the border-member; means inwardly of the border-member extending through the strip above and below the border-member, the underlying portion of the padding, and the filling, and terminating at the strip, said means securing said strip to hold the pad taut over the filling; and a box-border secured to the ticking sheet of the pad, the portion of the padding overlying the strip being confined against the strip by the connection between the pad and the box-border.

2. A mattress comprising, a central spring-structure including a border-member; a filling over the spring-structure having its margins folded around the border-member; a quilted pad over the filling comprising an inner liner, an outer ticking sheet and padding all stitched together separately from the filling; a strip having its inner margin interlaid in the padding of, and secured only to, the pad, the underlying portion of the padding extending over the filling above the border-member and being folded around and under the filling around the border-member; staples inwardly of the border-member extending through only the strip above and below the border-member, the underlying portion of the padding, and the filling, the staples securing the strip to hold the pad taut over the filling; and a box-border secured to the ticking sheet of the pad, the portion of the padding overlying the strip being confined against the strip by the connection between the pad and the box-border.

HAROLD KIBITZ.
